UNITED STATES PATENT OFFICE.

JAMES M. DODDRIDGE, OF MILTON, INDIANA.

GRAVE COVER.

Application filed July 31, 1926. Serial No. 126,148.

The object of this present invention is to provide a grave cover whereby after a grave has been formed it may be covered in such manner as to give the appearance of grass or 5 the surface of the ground in which the grave is formed, whereby the persons attending the interment will not see into the open grave during the interment and the services connected therewith.

Another object is to provide a grave cover which will open downward automatically as the casket is lowered, and will return to its normal horizontal position, covering the grave, as soon as the casket is lowered a 10 short distance into the grave, and during the interval between the opening and closing of the device, that is to say during the time the device is turned downward to let the casket pass into the grave, the device will form a 15 lining for the grave, whereby the side walls 20 of the grave can not be seen.

And, finally, broadly stated, my object is to provide a grave cover to be employed during an interment, and immediately prior and 25 subsequent thereto, the same being strong and durable in construction, neat and attractive in appearance, positive and automatic in 30 operation, adapted to be disassembled whereby it will occupy a comparatively small amount of space, which may be adjusted to 35 graves of various sizes, and which can be manufactured and sold at a comparatively low price.

Other objects and particular advantages 35 of this invention will be brought out in the course of the following description.

The preferred manner of carrying out the principles of my invention in a practical, efficient, and economical way, is shown in the 40 accompanying two sheets of drawings, in which—Figure 1 is a top plan view of my entire device in the position it would assume over a grave, but with imitation grass or other decorative means omitted therefrom in 45 order to show the details of construction. Figure 2 is a cross section, taken through a portion of the earth near the grave, and a portion of the grave formed therein, and of 50 my device in normal operative position in connection therewith. Figure 3 is the same as Fig. 2, except that a casket is shown as being lowered into the grave, showing a cross section of my device as it would appear 55 while the casket is being lowered. Figure 4 is a perspective view of a major arm. Fig. 5 is a section of a major arm. Fig. 6 is an end

view of the cam, with a running-board and cam spring in section. Fig. 7 is a side view of one of the ties. Fig. 8 is an edge view of one of the pivoting members and a portion of 60 its push arm. And Fig. 9 is a perspective view of a section of one of blankets, showing the manner of its attachment.

Similar indices denote like parts throughout the several views. 65

In order that the construction, the operation, and the several advantages of my invention may be better understood and appreciated, I will now take up a detailed description thereof, in which I will set forth the 70 same as comprehensively as I may.

In the drawings letter A denotes an open grave, and B denotes the earth or ground in which the grave is formed, the surface of 75 which is usually covered with grass or sod.

Letters C and D denote the side or long running boards, and E and F denote the end or short running boards, the four running boards together entirely surround the grave and lie flat on the surface of the ground B. 80

Letter G denotes a casket, for which the grave A is formed.

There are two sides of my device; each extending longitudinally of the grave A, and as each side is a duplicate of the other, therefore a description of one will answer for both. The parts which are identical in the two sides being denoted by the same reference characters in the following description. 85

Secured, detachably, to the surface of the board C (and D) are two main hinge members, 1 and 2, which project over the inner edge of the board C, where a bearing is formed at their inner ends. And midway between the members 1 and 2, also secured to 90 the board C, is an intermediate double hinge member 3.

Numeral 4 denotes the main shaft, which is divided near its center into two parts which are connected by a coupling 5. Said 100 shaft 4 is revolvably mounted in bearings formed on the inner ends of the members 1, 2 and 3.

Rigidly clamped on the rod 4 are six major arms 6, which are substantially L- 105 shaped, that is to say, their inner end portions are turned laterally at right-angles to their main portions, as shown.

Also two auxiliary arms 7 are provided, one at each end, which are likewise clamped 110 to the shaft 4, as hereinafter stated.

Each of the arms, 6 and 7, are secured to

the rod 4 as follows: A half-round channel 8 is formed across the face of each of said arms. A clamp member 9 rests on the face of each of said arms, and it has a half-round channel 10 formed across its contact face which registers with the channel 9, with the channels 8 and 10 almost surrounding the shaft 4 with which they engage and by which the arms and their clamps are secured to said shaft 4 by means of the bolts 11 and 12, as in Fig. 4.

Formed in and extending across the upper side of the clamps 9 is a U-shaped channel 13, for the purpose hereinafter set forth. 15 Formed in and extending across the body portion of each of the arms 6 and 7, is a channel 14. And likewise formed in and extending across the angular or inner end portion of the arms 6 is a channel 15, which is 20 at right-angles to the channels 14. The channels 14 and 15 are for the purpose hereinafter set forth.

Pivotal clips 16 and 17 are provided for the respective channels 14 and 15, the same 25 being pivoted to the surfaces of the arms 6, and are adapted to be turned over the respective channels 14 and 15, as shown in Fig. 1. Likewise pivoted to the surface of clamps 9 is a clip 18, which is adapted to 30 be turned over the channel 13, also as shown in Fig. 1.

Likewise the inner end-portions of the arms 7 are each provided with a channel 14, with a clip 19 adapted to be turned to cover 35 said channel in the arm 7, as shown in Fig. 1. The channels 14 in the arms 7 are in alignment with the channels 14 of the arms 6.

A comparatively small rod 20 extends 40 parallel with the shaft 4, having a coupling 21 in its center, and said rod 20 is adapted to rest in the channels 13 of all of the arms 6 and 7, where it is detachably secured by the several clips 19, as shown in Fig. 1.

Surrounding portions of the shaft 4 are two 45 coil springs, 22 and 23. The ends of each of said springs contact with the underside of one of the members 1 and 2, and with the underside of one of the arms 6, with the tension of said springs such as turn the shaft 50 4 to bring the arms, and other parts attached thereto, to horizontal inwardly directed position, as in Figs. 1 and 2, when released, but still permitting said arms to be turned downward to vertical position, as in Fig. 3, against the resiliency of said springs.

A cam 24 is secured on the central portion of 55 the shaft 4, being located between the prongs of the member 3, as in Fig. 1. And a cam spring 25 rests on the member 3, where it is secured by the same bolts 26 which secures 60 the member 3 to the running-board C. The free end portion of the cam-spring 25 contacts with the periphery of the cam 24. The purpose of said cam is to not only assist 65 the springs 22 and 23 in turning the rod 4,

but also, and primarily, to act as a cushion whereby the rod 4, and the parts carried thereby as hereinafter explained, will operate more slowly, that is without a quick snap when they are released.

Each side of the device includes three skeleton wings: a central and double main wing and two single end wings. Each of said end wings comprises two identical members, while the central or main wings each comprises four identical members.

Each of said wings proper, which I will now describe, is formed of comparatively heavy wire stock. The central wing consists of two main parts which overlap each other, as shown in Fig. 1.

Said central wing includes the members 27, 28, 29 and 30, all of which are parallel with the shaft 4. Extending horizontally, at right angles, from the ends of the respective members 27, 28, 29 and 30, are the respective cross members 31-32, 33-34, 35-36 and 37-38. The members 27, 31 and 32 are integral with each other. The members 28, 33 and 34 are integral with 90 each other. The members 29, 35 and 36 are integral with each other. And the members 30, 37 and 38 are integral with each other.

The members 27 and 29 overlap parallel with each other, and they are each secured in 95 channels 14, each by a clip 16, before mentioned.

The members 31 and 35 overlap each other and they are adapted to be secured together by a tie-member 39, which carries a set-screw for locking said members together, as shown in Fig. 7. In like manner the members 33-37, members 32-36, and the members 34-38, are adapted to be adjustably secured together, each by one of the tie-members 39 shown in Fig. 7.

Each of the end wings comprises two parts which overlap each other, as in Fig. 1. Each end wing comprises two members which are identical with each other, and 110 each consists of a member 40, and 41, respectively, which are parallel with the shaft 4. Extending horizontally at right-angles from the ends of the members 40, are the two members 42 and 43; and extending horizontally at right-angles from the ends of the member 41 are the two members 44 and 45.

The members 42-44; 43-45; 42-44 and 43-45, are adapted to be adjustably secured together by one of the tie members 39, as 115 120 Fig. 7.

It is to be understood that there must be spaces between the ends of the main or central wing members and the end members of the wings. The purpose of this, and 125 therefore the purpose of the end wing members, is to provide a space near each end in which lowering straps may be operated when the casket is being placed in the grave. Two push arms are carried by each central 130

or main section of the wings, and each comprises: a hollow L-shaped member 46, and an L-shaped but smaller similar member 47. The straight portion of the member 47 being adapted to slide into the member 46, whereby the combined length of the two members may be varied, in other words, they are adapted to telescope together, as indicated. The curved end portion of the members 47 are pivoted to the central portion of the members 28 and 30, from which they extend upward and inward, and then straight into the member 46.

A pivoting and supporting member 48 is secured to the curved end portion of each of the members 46, from which it extends over the shaft 4, and is pivoted to the member 27 (or 29), where it is detachably secured by the clip 48 carried thereby. There also being an upwardly curved portion 50 formed in the member 48 to fit over the shaft 4, as in Fig. 8, but without attachment thereto.

The primal object of the wings above described is to carry, and support, in proper position, blankets made to simulate grass or sod, or the like. Said blankets each comprises a top 51 of artificial grass, which is made on a backing 52 formed of wire netting or burlap, or other material. Secured to the underside of the blankets and spaced at frequent distances apart along the outer edge thereof are hooks 53, which are adapted to be engaged on the rod 20, whereby when the wings are turned down to near vertical position the blankets will not slide down into the grave, but will hang from said rod 20.

Said blankets extend from the rod 20 over all of the parts of said wings, except the push-rods formed by the members 46 and 47.

In practice the device is assembled and placed over the grave, in the position shown in Figs. 1 and 2. The device is then covered over with six separate sections of the blankets, which of course completely covers the grave. One of the said sections of the blankets is placed on each of the two main sections, and on each of the four end sections, of the wings, extending them over the edges thereof, whereby the grave will not show, and with the blankets meeting, or nearly so, in the spaces between the main wing members and the end members of the wings. The outer edges of the blankets being hooked onto the rod 20.

The casket G may now be lowered into the grave in the usual manner. As the casket moves downward it will of course engage the two sets of push-arms, whereby the wings of my device will be turned downward thereby against the walls of the grave, or nearly so, thereby permitting the casket to slide through between the two wings.

As soon as the casket has passed below the wings which it has pressed apart, it is evident that as the wings are released that the springs 22 and 23 will return the wings to their normal horizontal position, thereby again closing the grave.

After the interment services have been completed, and before the grave is filled in, then my device may be removed and disassembled, and packed into a comparatively small space, for transportation or storage.

It is to be understood that various changes may be made in the several details of construction, from that shown herein, without departing from the spirit of the invention, and without sacrificing any of the advantages thereof which are new and useful.

Having now fully shown and described my invention, what I claim and desire to secure by Letters Patent of the United States, is—

1. A grave cover consisting of two sets of wings, the two sets of wings being adapted to be located on opposite sides of a grave with relation to each other, a shaft for each set of wings and to which the respective wings are connected, each set of wings comprising a main wing and an end wing located on each side of the main wing, each of the end wings being composed of two members which are identical with each other, and each main wing being composed of four members which are identical with each other, springs for normally holding said wings in horizontal position but permitting them to be turned downward to vertical position, stops for preventing the wings from moving upward beyond horizontal position, blankets adapted to cover said wings, and means for detachably securing said blankets to the wings whereby they will not slide when the wings are being turned to vertical position.

2. A grave cover comprising two sets of wings each hinged to a shaft which shafts extend parallel with each other on each side of a grave, springs retaining the wings in horizontal position but permitting them to be turned downward to vertical position inside the grave, means whereby various parts may be adjusted by which the device may be assembled to fit graves of various sizes, blankets adapted to cover the various portions of the wings, means for attaching said blankets to the wings, and means whereby the device will be pressed downward by the lowering of a casket without the casket interfering with said blankets.

3. In combination with an open grave and running boards located on the ground around the grave, a wing hinged to each of the two longer running boards and normally extending to near each other over the grave, springs retaining said wings normally in extended horizontal position but permitting them to be turned downward to vertical

position to permit the passage of a casket between the wings, means whereby said wings are adapted to be adjusted to various lengths and widths in order to cover graves of various sizes, and means whereby the parts may be separated for the purpose of placing them into a small compass of space.

4. In combination with an open grave having a run-board located on the ground on each side thereof; a grave cover comprising a skeleton wing for each side of the grave, bearings attached to each of said run-boards, a shaft rotatable in each set of bearings, means for rigidly connecting the outer edge of each wing to its respective shaft, a blanket adapted to cover and rest on each wing, means for detachably connecting the outer edge of each blanket to its respective wing, springs for resiliently causing each wing to assume horizontal position over the grave but permitting it to be turned down to vertical position to form a lining for the sides of the grave, means for preventing the wings from turning upward beyond horizontal position, and a cam mechanism for con-

trolling the speed of movement of the wings when they are released.

5. In combination with run-boards located outside and on each side of a grave, a shaft located parallel with and near to each run-board, means for rotatably connecting each shaft to its run-board, a wing rigidly connected to each shaft, each wing comprising a skeleton frame-work, springs connected to each wing and normally causing their wings to move to horizontal position when the wings are released but permitting them to be forced downward to vertical position inside the grave, means for preventing the wings from rising upward beyond horizontal position, a cam mechanism connected to each shaft to cushion the upward movements of the wings, a blanket covering each of said wings, means for detachably connecting the outer edge of each blanket, and means whereby all of said parts may be detached from each other whereby they may be packed into a comparatively small space.

JAMES M. DODDRIDGE.
